(57) **CLAIM**

The ornamental design for a wireless communication hub as shown and described.

DESCRIPTION

FIG. 1 is a perspective view of a wireless communication hub showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, showing antenna in a raised position; and,

FIG. 9 is a perspective view thereof, showing antenna in a rearward position.

The broken lines showing of portions of the wireless communication hub form no part of the claimed design.
